ELECTRICAL SWITCH UNIT

Joseph F. O'Brien, Jersey City, N. J., assignor to
 John B. Pierce Foundation, New York, N. Y., a
 corporation of New York

Application July 7, 1939, Serial No. 283,160

3 Claims. (Cl. 200—168)

This invention relates to improved electrical wiring systems, and particularly to an electrical switch device for use with electrical conductor-bearing elements of standard lengths and design, adapted to be connected in seriatim with each other and with said switch device to afford a continuous electrical wiring system.

In the presently co-pending application Serial No. 286,734, filed July 27, 1939, and entitled Electrical unit, there is set forth and claimed an improved electrical wiring system comprised of a plurality of standard units adapted to be interconnected in seriatim to form a continuous wiring system.

It is an object of the present invention to provide improved electric switch means for said system, the switch mechanism per se being disposed within a body adaptable for such seriatim connection.

Further, it is an object of the present invention to provide an improved electric switch means of simplified construction and design, in which the switch cover plate is employed to maintain the operating mechanism of the switch in proper operative position, or upon removal of the said cover plate, to permit removal of the switch mechanism as a unit by mere outward withdrawal of such unit.

It is yet another object of the invention to provide electrical switch means in which a jumper affording a permanently closed electrical circuit can be readily inserted in lieu of the switch mechanism, by removing the said switch mechanism as aforesaid and substituting therefor cover plate means associated with which is an electrical conductor-carrying element suitable to effect such closed connection.

Pursuant to the present invention, the electric switch includes an elongated body having a cap member and a composite base structure operatively associated therewith. The cap member is formed with a chamber or switch housing, preferably disposed adjacent an end of said cap member to provide an extension of said cap member which may be shortened if desired, as more fully set forth in the detailed description herein. A portion of said composite base structure is in direct operative association with said switch housing, and may be permanently secured thereto. Said base portion is provided with longitudinally extending electrical conductors to which are electrically connected switch contact means extending suitably into said switch housing, the said base portion serving to maintain said switch contacts in operative position within said housing.

5 A second element of said composite base structure is removably associated with the above mentioned extension of said cap member, and cooperates with said housing base to form a substantially continuous base. Said second base element is provided with insulatedly mounted electrical conductors; electrical connection between said conductors and the conductors within said housing base member may be made by removable pins of electrically conductive material.

10 The second mentioned base element may be provided with a wedge-like extension to form a male connection end of the said switch unit; the cap member at the end adjacent said housing cooperates with the housing base member to provide a female socket for interconnection with a male extension of a preceding conductor unit.

15 The switch mechanism per se may include any desired organization having a conductor element arranged to be brought into or out of engagement with said switch contacts. Desirably, said conductor element is pivotally arranged, the pivot means therefor being supported within open-topped bearings in said switch housing.

20 To maintain said pivot means within the said bearings, there is provided a cover plate for said housing, said cover plate having lugs or extensions arranged to overlie the said open-topped bearings to confine the pivot means therein.

25 Removal of said cover plate from the housing thereby frees the switch mechanism for complete removal from the housing, the removal of said switch mechanism being effected without any disconnection of the switch contact means from the conductor elements within the base portion.

30 Other features and advantages will be hereinafter more fully described.

In the accompanying drawings—

35 Fig. 1 is a fragmentary representation of an electrical circuit showing conductor elements connected in seriatim, the central element thereof being the switch element, pursuant to the present invention;

40 Fig. 2 is a plan view of an electrical switch means pursuant to the present invention, the switch cover plate having been removed;

45 Fig. 3 is a sectional elevation taken on lines 2—3 of Fig. 2;

50 Fig. 4 is a vertical transverse section through the switch on the lines 4—4 of Fig. 2;

Fig. 5 is a vertical transverse section through the switch on the lines 5—5 of Fig. 2;

Fig. 6 is a perspective of a portion of the switch housing;

Fig. 7 is an exploded perspective of a base assembly for the switch housing;

Fig. 8 is an exploded perspective illustrating the stationary contact and conductor elements of the switch mechanism, and the supporting structure therefor;

Fig. 9 is a fragmentary perspective view of the switch cover plate; and

Fig. 10 is a side elevation of a cover plate embodying an electrical jumper connection.

Referring to the drawings, Fig. 1 shows so much of an electrical circuit as is necessary for an understanding of the present invention. In such circuit, conductor carrying units 10, 11, desirably of standard length, embody preferably tubular conductor elements 12, 12.

A switch unit 14, forming the subject matter of the present invention, is illustrated in mechanical and electrically conductive association with the stated conductor elements 10 and 11. The mechanical engagement, as hereinafter described, is effected by an interfitting male and female joint association with contiguous units, and the electrical connection is desirably effected by the insertion of electrically conductive pins into contiguous tubular conductors.

Referring to Figures 6, 7, and 8, the electrical switch unit 14 includes a cap member 15, a base member 16 comprising elements 16a, 16b, and a contactor base plate 17. The base member 16 is preferably mechanically separable from the cap member 15.

Switch cap member 15 is formed with a suitable boxlike switch housing 18, said switch housing including spaced switch fulcrum shaft cradle posts 20 and a sub-base or shelf 21, in which shelf is provided a suitable transversely arranged aperture 22. An end 15a of said switch cap 15 remote from the stated switch housing is arranged to cooperate with base 16, to provide male end connection means, as shown in Fig. 3; the opposite end 15b is provided with a suitable tapered socket 24 arranged to receive the male connection end of a preceding unit, such as the unit 11, Fig. 1.

Base elements 16a and 16b have formed therein matching arcuate grooves 25, 25, combining to form longitudinal tubular passages within which may be held the desirably tubular electrical conductor elements 12, 12. Desirably, the said base elements are entirely of electrical insulation material, and the conductor elements are maintained in electrically insulated relationship.

To facilitate the assembly of said base elements, it may be desirable to provide one of said elements, as 16a, with suitable apertures 26, for cooperative association with pins or tongues 27, 27 provided on the underside of the complementary base element 16b.

The use of rubber, or a suitable moldable plastic in which a final step of curing or vulcanization may be effected after the conductors 12 have been inserted into the stated longitudinal tubular passages, provides for the integration of the base into an inseparable unit within which the said conductors are immovably positioned.

The contactor plate 17, also desirably wholly of electrical insulation material, is provided with an upstanding slotted post 36, arranged to support a stationary switch contact member 37. As clearly shown in Figs. 2 and 3, the contact member 37 may be secured to said post 36 by a suitable screw 38 passing through an opening in an ear 39 into a suitable screw threaded aperture in the post 36.

Switch contact 37, see Figs. 4 and 7, may be provided with a tapered pin conductor element 42 for electrically conductive engagement with a tubular conductor 12. Said element 42 may be secured to the switch element 37 by bending an extension of said switch contact about pin 42 and brazing or soldering the same. Switch contact 37, therefore, is maintained in rigid operative position through the combined effect of the walls of the slotted post 36, which embrace the vertical portion of the switch contact and the blade portion thereof relatively closely, and the arcuately domed passage 43 at the base of said post 36, said passage 43 snugly overlying switch contact 37 at its junction with conductor pin 42.

A suitable recess 45 is provided in the surface of contactor plate 17, said recess being configurated to include a central body portion adequate to accommodate the under side of the complementary switch contact element 46. Said element 46 is formed with two flat projecting ears 47, 47, adaptable to rest upon a shelf 48 provided at a side of said recess 45. The depth of shelf 48 is desirably equal to the thickness 25 of the ears 47, so that the assembly of the plate 17 against the under side of sub-base 21, clamps the contact ears tightly.

The vertical contact post of switch contact 46 is of suitable length to project upwardly through the aperture 22 formed in lower shelf 21, as shown in Fig. 5, it being understood that the width of said aperture corresponds to the width of switch contact 46 so that said contact may be firmly supported; as shown in Fig. 5, contact 46 is clamped between the sub-base 21 and the plate 17.

The conductor element 50 of switch element 46 is desirably tubular, so that electrical connection with a preceding conductor element may be made by suitable electrically conductive pins. The companion conductor element 51 is maintained in spaced and electrically insulated position within a tubular passage formed by suitable cooperating arcuate grooves respectively in the plate 17 and sub-base 21.

Electrical contact between tubular conductor 51 and the contiguous electrical conductor 12 of the base assembly unit may be made by the insertion of the tapered electrically conductive pin 42a.

Contactor base plate 17 may be suitably permanently secured to the under side of the switch chamber shelf 21, as by cementing or like treatment. It is noted from Figure 3 that plate 17 is equal in length to the shelf 21, to the end that the edges of said plate 17 and shelf 21 may align to form a square end wall of the female socket 24. It is noted further, that said plate 17 is provided with a foot or extension 53, which projects beyond the joint between the base 16 and the shelf 21 to close the said joint against any possibility of accidental short circuit.

In like manner, base 16 is provided with an extension 54 for cooperation with the female socket portion of the next succeeding conductor unit.

Upon the assembly of the switch cap 15 with the plate 17 the respective stationary switch contacts 37 and 46 are immovably positioned, and the electrical connection of such contacts with the conductor elements of the assembled wiring system is substantially entirely concealed within an electrically insulating structure. As presently described, the switch mechanism is removable 75 as a unit without the disconnection of the said

switch contact members from the conductor elements of the said wiring system.

The switch mechanism per se is illustrated as of the tumbler type, and includes a suitable switch button 55 provided with a fulcrum shaft 56 arranged to fit snugly and rotatably within open-topped bearings 56a provided in the said cradle posts 20. Suitably secured to said button 55, as by integral molding therewith, there is provided a forked switch toggle arm 57, for operative association with a switch toggle spring arm 58. A U-shaped switch toggle 60 is freely rotatably mounted on the switch button shaft 56. A suitable movable switch contact 61 may be secured to an arm of toggle 60, in Fig. 2, and may be spaced from said toggle arm by a suitable intermediate insulation block 62.

As shown in Fig. 3, switch toggle spring arm 58 has a transverse bar suitable for insertion into the forked end of the member 57. The opposite end of said spring arm extends into and through a suitable opening in switch toggle 60, and a conventional coil spring 63 completes the assembly. Operation of the switch button 55 compresses the spring 63 until the overthrow point is reached, whereupon the reaction of the spring throws the toggle 60, which carries the switch contact 61 either into or out of electrical engagement with the stationary switch contacts as understood by those skilled in the art.

To limit the movement of the switch button 55, I provide the said button with a nose 55a which operates between spaced posts 59, 59a formed in the base of the switch chamber shelf 21.

It is a feature of the present invention that the switch operating mechanism is readily removable as a unit, without disturbing the electrical connection between the stationary switch contact posts and the conductors of the wiring system.

As stated, the switch fulcrum bearings 56a provided in the cradle posts 20 are open-topped. The fulcrum shaft 56 is thus readily inserted into the bearings from above. To hold the shaft 56 within the bearings and to maintain the switch mechanism in proper alignment and operative relation with respect to the contacts 37, 46, the switch cover plate 65 is provided with downwardly extending lugs 66 of electrical insulation material. The lugs 66 are positioned and proportioned for a snugly slidable association with the slots 67, see Fig. 6, provided in the side walls of the switch chamber 18 in suitable operative association and register with the cradle posts 20. The terminal portions of said lugs abut against the upper surface of the respective cradle posts 20 to close the bearings 56a against removal or upward displacement of the fulcrum shaft 56.

Switch cover plate 65 may be entirely of electrical insulation material, the lugs 66 being integral therewith. Suitable screws 68, 68 may be employed to affix the cover plate to the cap 15.

Removal of the plate 65 frees the fulcrum 56, and the entire switch mechanism may be removed as a unit, merely by grasping the switch button 55 and drawing the mechanism outwardly. Such procedure is best accomplished when the switch is in its "off" position, in which position the contact arm 61 will be out of engagement with the contacts 37, 46.

The manner in which the entire switch mechanism may be removed offers an additional advantage of appreciable practical importance: a jumper may be provided to substitute for the switch mechanism in making a permanently

closed circuit, in circumstances where it is not desirable to provide the facilities of a switch. Such jumper may be provided on the underside of a solid cover plate 70, see Fig. 10, equal in size and similar in configuration to the switch plate 65. The jumper may comprise suitable spring contact elements 71, 72, of such length as to engage the respective stationary switch contacts 37, 46, with a bridging conductor 73 extending between said contact members 71, 72 to afford a completed electrical circuit. The switch unit may be removed, as aforesaid, and the jumper inserted, the spring contacts of such jumper electrically connecting with the stationary contacts 37, 46, within the switch housing 18. In this manner, a continuously closed circuit may be maintained.

It is noted that the female socket and the male end of the switch unit 14 are provided with screw-passages 80, 80. In an assembly of the switch unit with contiguous conductor carrying units, see Fig. 1, the screw-passage at the socket end of one unit registers with the passage of a male end of the interfitting unit, and a wood screw or equivalent may be employed to fasten the assembly to a building moulding, studding, or the like.

Whereas I have described my invention by reference to specific forms thereof, it will be understood that many changes and modifications may be made without departing from the spirit of the invention.

I claim:

1. An electric wiring device, comprising a body, a chamber formed therein, said chamber having bearing means formed therein and slot means formed in a wall of said chamber above said bearings and in register therewith, switch contact elements disposed within said chamber, electric circuit breaker means disposed within said chamber and having shaft means for rotatable support upon said bearing means, and cover plate means for said chamber, said cover plate means having downwardly extending lugs arranged for slidible insertion into said slot means, the termini of said lugs overlying the said shaft means to maintain the same in operative engagement with said bearing means.

2. An electric switch, comprising a body, a chamber formed therein, said chamber having aligned cradle means, contact elements positioned within said chamber, electric circuit breaker means removably positioned within said chamber for operative association with said contact elements, said circuit breaker including a fulcrum shaft arranged for pivotal engagement with said cradle means, and cover plate means for said chamber, said cover plate means having lugs arranged for cooperative association with cradle means to maintain the said fulcrum shaft in operative association with said cradle means.

3. An electric switch, comprising a body, a chamber formed therein and having aligned shaft-supporting means arranged adjacent opposite walls of said chamber, electric circuit breaker means positioned within said chamber and having a shaft arranged for disposition within said shaft-supporting means, and means arranged to be secured to said chamber to maintain the circuit breaker means therein, said means including lugs arranged for closely fitting engagement with the side walls of said chamber adjacent said shaft-supporting means and adapted to overlie the shaft to maintain said shaft within said supporting means.

JOSEPH F. O'BRIEN.
